KNIFE OR THE LIKE

Albert M. Baer, New York, N.Y., assignor to Imperial
Knife Associated Companies, Inc., Providence, R.I., a
corporation of Rhode Island

Filed Feb. 3, 1964, Ser. No. 78,493

Term of patent 14 years

(Cl. D22—3)

FIG. 1 is a front elevational view of a knife or the like showing my new design;

FIG. 2 is a right-side elevational view thereof;

FIG. 3 is an enlarged front elevational view of the portion of the blade of the knife bounded by the circle in FIG. 1, the same being illustrative of the difference in surface ornamentation of different areas of the broad surfaces of the knife blade; and

FIG. 4 is an enlarged sectional view through the knife, the same being taken substantially along the line 4—4 of FIG. 1.

The dominant feature of my new design resides in the ornamentation applied to the blade, such ornamentation constituting a specular finish of substantially uniform width forming a highly reflective band running along the length of the marginal zone adjacent the cutting edge and a finely striated finish extending from the reflective band a substantial distance toward the blunt edge. The design is intended for use on knife blades.

I claim:

The ornamental design for a knife or the like, substantially as shown and described.
